UNITED STATES PATENT OFFICE.

DELBERT D. PARKER, OF ELBA, NEW YORK, ASSIGNOR TO BURT MACHINE COMPANY,
INCORPORATED, A CORPORATION OF MARYLAND.

WRAPPING MACHINE.

Application filed August 24, 1923. Serial No. 659,063.

This invention is an improvement on the machine described and shown in United States Patent No. 696,218, March 25th, 1902, to Whitehurst, et al. This patent is entitled 5 "Labelling machine", though the machine which it describes and shows might more properly be termed a wrapper than a labeller in that it wraps and folds a paper cover which entirely encloses the cans both as to 10 their cylindrical sides and the flat ends, as distinguished from the labelling machines which merely roll or wind a strip of paper which serves as a label about the cylindrical surfaces of the cans.

15 The machine referred to operates somewhat after the manner of a labeller in that the cylindrical cans are rolled through the machine by contact with an endless belt, and as they pass, each can picks up a sheet of 20 paper or wrapper, which is wound or rolled about the cylindrical surface as the can rolls forward along the ways, but the wrapper differs from the ordinary labeller in that the 25 sheets of paper wrappers are longer transversely than the axes or height of the cans, and the machine includes means for folding or turning the edges of the paper in to 30 cover the circular ends of the cans.

The present invention relates to this feature of the machine, i. e., to the mechanism for folding and pressing the edges of the paper thus turned in to cover the ends of the cans.

The machine illustrated in the patent referred to, is, however, merely adapted for handling straight or flattened cans, and even with this type of can the closure of the wrapper formed by turning in the edge portions over the circular ends of the cans, was 40 not quite sufficiently rolled and pressed to give in each and every instance a neat and presentable package.

The object of the present invention is to produce a machine or to so improve the machines in existence that they will fold and press the paper about the ends, giving a completed package of neat and finished appearance in every instance, whether the cans be of the flat-ended type or those having a 45 depression in the ends, such as the sanitary cans and other cans, large numbers of which are made with such a depression, a slight depression being produced in practically all cans by the vacuum incident to cooling, so 50 that even with the supposed flat-ended cans

the wrapping operation is apt to be more or less defective with the old machine on account of failure to properly press the wrapper when it is folded over the ends of the cans.

60 In the accompanying drawing I have illustrated a machine embodying my invention in the preferred form.

65 In the drawing Figure 1 is a fragmentary side elevation showing the front or delivery end portion of the machine.

Figure 2 is an elevation looking at the machine from the right as it is seen in Figure 1, i. e., a front end elevation.

70 Figure 3 is a slightly enlarged view corresponding to Figure 1, a partially wrapped can in the process of pressing the wrapper at the ends being shown in the grip of the rollers, the can and wrapper being sectioned for convenience of illustration and the view 75 being broken away as to both the can and the roller, only one roller being shown.

Figure 4 is a section taken on a plane of 80 the axis of the presser roller forming part of my improvement.

Figure 5 is a section through the roller on the line 5, 5 of Figure 4 taken at right angles to the axis.

Figure 6 is a section showing one of the 85 delivery rollers, the same being taken on a plane of the axis.

Figure 7 is an elevation showing the manner of mounting and supporting the upper end of the presser roller spindle, and

Figure 8 is a plan of the same.

90 Referring to the drawing by numerals, each of which is used to indicate the same or similar parts in the different figures. The machine which is fragmentarily illustrated in Figure 1, is in structure and general operation substantially the same as that shown in the patent above cited, in that it has longitudinally-extending ways 1, along which the cans roll, propelled by a feed belt 2 which engages them from above. In the 100 present instance there are two feed belts 2, 2 spaced slightly apart for propelling the cans through the machine for the greater portion of the length thereof, and a central feed belt 3 which engages the cans near the 105 end of the traverse, bringing them into the bite of the delivery rollers 4, 4, see particularly Figure 1. This latter belt is actuated from the pulley 7, which carries the feed belts 2, 2 or from the shaft 9 thereof, to 110

which is secured a pulley member 8 which is of slightly larger diameter and which carries the delivery feed belt 3, the same being also laid over a small idler pulley 9 a few inches back of the pulleys 7, 8 and so placed that the bottom reach of the delivery feed belt is but slightly above the level of the operative portion or bottom reach of the main feed belts 2, 2.

10 Co-operating with the delivery belt is a yielding can support 10 which is placed parallel to and between the ways 1, being pivotally mounted on a bolt 11 seated in the frame and extending transversely. As 15 shown the support 10 is in the form of a lever which extends both forwardly and rearwardly from the pivotal bolt 11. The forward end of the member 10 is supported on a helical spring 13 in a suitable spring socket 14 secured to the frame, the spring being centered and aligned by means of a pin 15 which is vertically placed in the socket and surrounded by the spring, the upper end of the pin being threaded into 20 the support at 16 and the lower end of the pin being passed through an opening 17 in the bottom of the socket through which it passes freely, the upward motion of the pin being limited by nuts 18 threaded on its 25 lower end outside the socket and bearing against the portion of the socket adjacent the opening. The forward end of the support includes a raised portion or hill 19 over which the cans pass into the grip of the delivery rollers as hereinafter described. The delivery belt engages the can packages firmly as these are then raised by the support.

40 Adjacent the ways I have shown plows or dogs 6 for turning in the edges of the wrappers as the cans approach the delivery end of the machine. The mechanism for feeding and presenting the wrappers is not illustrated.

45 At the rear end of the machine, directly in transverse alignment with the axes of the pulleys 7 and 8, I have shown at each side of the path of the cans, the delivery rollers 4, 4. These are mounted each on a vertical 50 shaft or spindle 20, see Figure 1, each shaft carrying a bevelled gear 21 secured thereto, which in turn engages a small bevelled gear 22 secured to the pulleys 7, 8 or the shaft 9 thereof.

55 Forward of the delivery rollers I have shown presser rollers 25, 25 which are yieldingly mounted to swing in a transverse plane. In the form of the invention shown these rollers are mounted on vertical spindles 26, each of which has a bearing at its lower end at 27 in a suitable bearing block secured to the frame in any suitable manner as by a bolt 28. The spindles are mounted at their upper ends in brackets 29 secured to the frame by bolts 30, see Figures 7 and 8,

the brackets being slotted or provided with slightly elongated apertures 32, which permit a slight transverse play, so that the rollers yield outwardly in response to the pressure of the rollers against the cans or the reaction of the same. 70

In the form of the invention shown, each spindle 26 carries near its upper end a sleeve 34, which is circumferentially grooved at 35, which groove is engaged by a spring wire 36 which encircles the sleeve, and which, as shown, is bent back upon itself substantially in the form of a U, being also looped at 37 and 38 providing for engagement by screws, by means of which it is secured to the bracket. The springs 36 tend to thrust the rollers or the upper ends of the spindles inwardly toward the center of the ways. The sleeve 34 may also act as a bearing for the roller spindle. The spindle is held in position in the form of the invention shown, by a clip 40, see Figures 7 and 8, secured by screws 41 and 42. The clip may be removed from the path of the spindle by removing either one of the screws 41 and 42, and swinging the clip to the right or left. The spindle and roller are removed by raising them until the spindle is released from the bearing 27. 80

90 The delivery roller 4 and the presser roller 25 are of interest. These rollers are formed with a wood or metal body, or center portion 44, 45. Referring to the respective rollers, which may be formed on or secured to the respective spindles 20 and 26, the body or center portion of wood or metal, is covered by a jacket 46, 47 of flexible rubber which is preferably of approximately the quality used for the treads of automobile tires. In this way I produce a roller having all the necessary resilient properties and of greater length of life than the ordinary rubber roller made of a single piece of material, in that there is no tendency for it to crack or break into segments after the manner of such rollers. The outer casing or jacket has not only great flexibility but considerable tensile strength, and the inner portion having greater resistive qualities than ordinary block rubber. 100

110 Having particular reference to Figure 4, it will be noted that the presser roller is of increased diameter or bellied out centrally, and for the greater portion of its length, the enlarged portion of the core being indicated by reference character 48, and the enlarged portion of the outer diameter by reference character 50. It will be further noted from Figure 3 that the enlarged portion of the roller corresponds in length, measured in the direction of the axis, to the diameter of the depressed portions of the cans being treated, though the machine is capable of treating cans having a considerable variation as to the diameter, the important point 120

being that the enlarged or bellied portion of the rollers 25, in treating the cans with the depressed or hollowed out head portions, shall enter into the hollows or depressions, 5 pressing and setting the folded edges of the wrappers 56 which cover the ends of the cans, it being understood that the edge portions of the wrappers may be coated with paste or cement so that one function of the 10 presser rolls is not only to press the creases in the materials, completing the folding operation but to press the layers of paper together, giving the paste or cement an opportunity to set. The presser rolls thus formed 15 and mounted, enter and completely fill and contact with the entire end surfaces of the cans, engaging the entire area of the depressed portion, even though there be some considerable variation in the diameters of 20 the cans wrapped, the variation being provided for by the flexibility of the roller, and further the cans dwell for a short time between the presser rollers providing for setting of the cement and creases.

23 In the operation of the machine the cans are fed to the ways in any suitable manner, a supply of wrappers being maintained in or directly beneath the path of the cans as described in the patent above cited, or in 30 any preferred way. The cans may be touched with adhesive or otherwise caused to take up the wrappers as they pass, the rolling motion of the cans causing the wrappers to be rolled about the cans. In this 35 operation wrappers are, as aforesaid, provided which are of greater width than the length of the cans, so that when the wrappers are rolled about the cans as described, the edge portions project beyond the cans.

40 These edge portions are folded in by contact with the plows 6, see Figure 1, immediately following which operation the cans are raised by passing over the hill 19 on the pivoted support 10, in which portion of their 45 path they are held between the short tight delivery belt 3, and the support 10, which is spring-pressed by the springs 13, as previously described, and the action of the delivery belt 3 carries, and to some extent 50 forces the cans into the bite of the delivery rollers 4 which engage the cans by their end surfaces, pressing them to such extent as the straight formation of the rollers permits and holding them in the elevated position to 55 which they are raised by the support 10, so that while gripped by the rollers they are out of contact with the support and the ways, and thus relieved from any tendency 60 to rotate as the belt 3 turns upward immediately beyond the bite of the delivery rollers 4. The delivery rollers 4 in turn deliver the cans thus wrapped one at a time to the 65 bite of the presser rollers 25, which as aforesaid enter the depressions in the hollow-headed cans, engaging the entire surface of

the hollowed portion or the wrapper folded over the same, completing the pressing operation as to the folded ends of the wrappers, and setting the cement.

It is further of interest that the presser 70 rolls, not being driven, have no feeding or delivery action, so that each can dwells in the bite of these rollers until it is pushed forward by the can next delivered by the delivery rollers. This dwell gives an opportunity for the paste to set, and completes 75 pressing of the folded portion. The yielding action of the rollers provides for a variation of the length of the cans, and equalizes the pressure applied. It is of interest 80 that the short delivery belt 3 is placed slightly above the level of the feed belt 2, engaging the cans as they are raised on the hill 19 of the support with considerable tension, more than can be applied by the longer 85 belt and delivered almost positively by the action of the belt and the support into the bite of the delivery rollers 4.

I have thus described specifically and in detail a portion of a machine embodying my 90 invention in the preferred form, in order that the nature and operation of the same may be clearly understood. However, the specific terms herein are used descriptively 95 rather than in a limiting sense, the scope of the invention being defined in the claims.

What I claim and desire to secure by Letters Patent is:

1. In a machine for wrapping cans, ways including a support having a raised portion 100 to raise the cans, means for feeding the cans along the ways, means for folding the edges of the wrappers over the ends of the cans, and a pair of rollers of yielding material having their axes vertically placed, and 105 means for rotating said rollers to press the wrapper on the ends of the cans and deliver the cans.

2. In a machine for wrapping cans, ways, a support having a raised portion to raise the cans before the ways, means for feeding the cans along the ways and support, means for folding the edges of the wrappers over the ends of the cans, and a pair of presser rollers placed with their axes vertical and having an enlarged central portion adapted 115 to receive and engage the cans, pressing their end portions as they are delivered from the bite of the feeding means.

3. In a machine for wrapping cans, an elongated support, an endless belt for feeding the cans along the support, folding means at the sides of the support to engage and fold the edge portions of wrappers over the ends of the cans, means for raising the cans as they pass the folding means, a pair of delivery rollers having their axes vertically placed to engage the cans by the end surfaces, and means for driving said rollers 125 advancing the cans and holding them in 130

raised position so that they are out of contact with the support, and a pair of presser rollers beyond the delivery rollers having their axes likewise upright and adapted to receive the cans from the bite of the delivery rollers, both sets of rollers serving to press and set the wrapper where it is folded over the ends of the cans.

4. In a machine for wrapping cans, an elongated support, an endless belt for feeding the cans along the support, folding means at the sides of the support to engage and fold the edge portions of wrappers over the ends of the cans, means for raising the cans as they pass the folding means, a pair of delivery rollers having their axes vertically placed to engage the cans by the end surfaces, and means for driving said rollers, advancing the cans and holding them in raised position so that they are out of contact with the support, and a pair of presser rollers beyond the delivery rollers having their axes likewise upright and adapted to receive the cans from the bite of the delivery rollers, the presser rollers being idle, so that each can dwells therein until it is pushed forward by the next can delivered by the delivery rollers, both sets of rollers serving to press and set the wrapper where it is folded over the ends of the cans.

5. In a machine for wrapping cans, an elongated support, an endless belt for feeding the cans along the support, folding means at the sides of the support to engage and fold the edge portions of wrappers over the ends of the cans, means for raising the cans after they pass the folding means, a pair of delivery rollers having their axes vertically placed to engage the cans by the end surfaces, and means for driving said rollers, advancing the cans and holding them in raised position so that they are out of contact with the support, and a pair of presser rollers beyond the delivery rollers having their axes likewise upright and adapted to receive the cans from the bite of the delivery rollers, the presser rollers having a flexibly supported surface and being of enlarged dimension intermediately, so that they enter and fill the hollows of cans having depressed end portions, pressing and setting the wrapper where it is folded over the ends of the cans.

6. In a machine for wrapping cans, an elongated support, an endless belt for feeding the cans along the support, folding means adjacent the support to engage and fold the edges of the can wrappers over the ends of the cans, a yielding support beyond the folding means, having a raised portion to raise the cans above the level of the support, a second feed belt above and co-operating with said support, delivery rollers hav-

ing their axes vertically placed, receiving the cans from the raised portion of the support engaging them by their ends and advancing them at the higher level to which they have been raised, and means for driving said rollers, the rollers serving to press and set the wrappers where they are folded over the ends of the cans.

7. In a machine for wrapping cans, an elongated support, an endless belt for feeding the cans along the support, folding means adjacent the support to engage and fold the edges of the can wrappers over the ends of the cans, a yielding support beyond the folding means having a raised portion to raise the cans above the level of the support, a second feed belt above and co-operating with said support, delivery rollers having their axes vertically placed receiving the cans from the raised portion of the support, engaging them by their ends and advancing them at the higher level to which they have been raised, means for driving said rollers, and presser rollers likewise mounted with their axes vertical, so that they engage the ends of the cans, the presser rollers being mounted to yield laterally and being of increased dimension as to their central portion, so that they enter the hollows in the ends of the cans having depressed end portions, pressing and setting the can wrapper where it is folded over the end of the can.

8. In a machine for wrapping cans, an elongated support, an endless belt for feeding the cans along the support, folding means adjacent the support to engage and fold the edges of the can wrappers over the ends of the cans, a yielding support beyond the folding means having a raised portion to raise the cans above the level of the support, a second feed belt above and co-operating with said support, delivery rollers having their axes vertically placed receiving the cans from the raised portion of the support, engaging them by their ends and advancing them at the higher level to which they have been raised, means for driving said rollers, and presser rollers likewise mounted with their axes vertical, so that they engage the ends of the cans, the presser rollers being mounted to yield laterally and being of increased dimension as to their central portion, so that they enter the hollows in the ends of the cans having depressed end portions, the presser rollers being idle, so that each can dwells therein until advanced by the pressure of the can next advanced by the delivery rollers.

Signed by me at Elba, Genesee County, State of New York, this 20th day of August, 1923.

DELBERT D. PARKER.
